UNITED STATES PATENT OFFICE.

EARL M. EVLETH, OF GRAND HAVEN, MICHIGAN, ASSIGNOR TO THE BASTIAN-BLESSING COMPANY, OF CHICAGO, ILLINOIS, A CORPORATION OF ILLINOIS.

ACETYLENE GENERATOR.

Application filed August 4, 1925. Serial No. 48,023.

This invention relates to acetylene generators of the portable type in which the generator is provided with wheels whereby it may be moved to the point of use for generating the gas as required.

The main object of my invention is to so design and construct the parts that the operator may give his undivided attention to the moving of the generator when occasion demands, and to prevent the possibility of his attention being distracted by the handling of a lighted torch during the moving.

A further object is to prevent the possibility of any further carbide being fed to the water, or any water splashing on the carbide during the shaking or jarring of the generator during movement, and to seal the communication between the water and carbide chambers so that the carbide cannot be submerged in the water with great evolution of gas and creation of dangerously high pressures, should the generator be upset during moving.

As one important feature I provide the apparatus with locking means connecting the valves with the running gear so as to prevent opening the valves when the running gear is unlocked, or unlocking the running gear when the valves are open.

As a further feature I provide the running gear with juxtaposed rotatable and non-rotatable supports either of which may be brought into operation, the movement of the truck being prevented when the non-rotatable support is in operation and the rotatable support is out of contact with the floor.

As a further feature I provide shifting means for bringing either the rotatable or the non-rotatable support into operation, said shifting means being locked against operation when the generator valves are open.

As a further feature I provide a handle member for moving the apparatus, and provided with means for automatically shifting the weight of the generator from the non-rotatable to the rotatable support upon the movement of the handle to operative position.

As a further feature I provide interlocking means whereby the handle cannot be moved to operative position while the valve mechanism is open.

As a further feature I provide interlocking means whereby the valve mechanism can-

not be opened while the running gear of the apparatus is released and free for operation.

Other objects, advantages and important features will be pointed out hereinafter or will be apparent from a consideration of the accompanying drawing and description of a preferred embodiment.

In the drawing:

Fig. 1 is a perspective view of a construction embodying my invention.

Fig. 2 is a vertical longitudinal section of a portion of the running gear, and

Fig. 3 is a sectional detail of a portion of the lock.

I have illustrated my invention as applied to a type of construction in which there is provided a truck having a frame 10 on which is mounted the acetylene generator. At one end the truck frame has hangers 11 carrying stud axles for the main wheels 12, 75 and at the other end has bearing blocks 13 for supporting a member 14 and permitting of the oscillation of said member about a transversely extending axis. This member 14 serves to rotatably support a downwardly 80 and forwardly inclined shaft or steering post 15 provided at its lower end with forks 16 in which is mounted a wheel 17. The bearing blocks 13 or adjacent portions of the frame, have a pair of legs 18 at the rear of and 85 upon opposite sides of the wheel 17. A draft handle 19 is connected to the head of the forks 16 so that upon turning the handle to the right or left the steering post and forks are oscillated, while upon swinging 90 the front end of the handle up or down the member 14 is oscillated. The parts are so positioned that when the handle 19 is in vertical position, as illustrated, the steering post is at such an angle to the vertical that the wheel 17 is lifted out of contact with the floor and the weight of the generator is supported in part by the legs 18. Upon swinging the handle forwardly and downwardly, the member 14 is rotated and the wheel 17 is forced downwardly and rearwardly between the two legs 18, so as to lift the latter out of engagement with the floor and support the entire load on the wheels 12 and 17.

It will be noted that the swinging of the handle downwardly to a position where it is convenient to pull or push the truck, automatically shifts the weight of the apparatus from the non-rotatable supports 18 to the rotatable support 17, while 105 110

the moving of the handle to upright position so as to be out of the way, shifts the weight of the apparatus back to the non-rotatable supports.

5 I do not wish to be limited to any particular type of acetylene generator, as the details of the generator, aside from certain features of the control thereof, form no portion of my present invention.

10 In the form illustrated there is a main water chamber and gas holder 20 above which is mounted a carbide hopper 21. The feed of the carbide may be automatically controlled in accordance with the gas pressure by some form of valve mechanism 22, but in connection therewith I provide means which when brought into operation, positively prevents the supply of carbide irrespective of gas pressure. This means is 15 shown as a valve 23 mounted on a rock shaft 24, which is connected by a link and suitable levers to a rock shaft 25 projecting to the exterior of the generator.

20 The generated gas may flow through a tube 26, a vibrator bell chamber 27, a pipe 28, a water-sealed flash-back chamber 29, to a manually operable shut-off valve 32 which should remain closed while the truck is being moved. Connected to the flash-back 25 chamber is a safety valve 30 and outlet 31 to give relief from excessive pressure.

25 In my improved construction I interconnect the draft handle 19, the steering and supporting wheel 17, the carbide feed valve 23, and the shut-off valve 32.

30 In the construction illustrated, the shut-off valve 32 is provided with an operating lever 33 which is connected by a link 34 to a lever 35 secured to the rock shaft 25 of the carbide feed valve. Therefore the lever handle 33 as it is moved upwardly and toward the right from the open position illustrated, acts to close the gas shut-off valve and at the same time close the carbide feed valve 23.

35 This valve operating mechanism is provided with means for preventing the opening of the valves when the weight of the truck is on the rotatable support 17. This means is shown as including a link 36 connected to the lever 35 and terminating in a locking bolt 37 vertically slidable in a guide 38 at the lower part of the frame. This guide also serves to support a bar 39 which is movable endwise and provided with an aperture which may be brought into or out of the path of the bolt 37. The closing of the valves 23 and 32 raises the bolt 37 out of the bar 39 so as to permit endwise movement of the bar. Any such endwise movement brings the aperture of the bar out of registry with the bolt and prevents downward movement of the bolt. This likewise prevents the opening of the valves 23 and 40 32.

45 The bar 39 extends to and is connected with a lever 40 mounted on a rock shaft 41, and the other end of the lever is connected by a link 42 to a catch 43 for holding the handle 19 in raised position. The swinging 70 of the catch out of the path of the handle so that the latter may be lowered, pushes on the link 42 and pulls on the bar 39 to bring the aperture of the latter out of registry with the locking bolt 37. 75

80 It will be noted that if the valves are open and the locking bolt is in operative position, the bar 39 cannot be pulled back, and therefore the catch 43 cannot be operated to release the handle 19. If the valves be closed 85 the handle may be released, but the releasing of the handle by the movement of the catch 43, so positions the bar 39 that the bolt 37 cannot be lowered and the valves cannot be opened. Furthermore, the oscillatory member 14 which is turned to bring the wheel 17 into operative position, is provided with an arm 44 which has a link 45, one end of which is slidable in an aperture in the lever 40. The link has a collar or stop 46 which 90 limits relative movement of the link 45 and lever 40 in one direction. With the parts in the position shown in the drawing the catch 43 may be operated to swing the lever 40 independently of any endwise movement 95 of the link 45. After the handle has been thus released, the downward movement of the handle to bring the wheel 17 into operative position, moves the link 45 endwise and brings the stop 46 again into engagement with the lever 40, and may even swing the lever further in the same direction as it was moved by the catch 43. Thus when the handle is down and the weight of the truck and the generator carried thereby is on the 100 wheel 17, the catch 43 cannot be operated to bring the bar 39 back to such position as will permit opening of the valves.

105 The gas shut-off valve 32 and the carbide feed valve 23 each constitutes a member for controlling the operation of the generator. By the broad term generator controlling member, I do not wish to be limited to the use of either of these two valves, or to the combination of the two, as other types of 110 generators may have other forms of controlling elements which it is desirable to lock against operation when the running gear of the truck is released. The drawing shows other forms of generator controlling members which are illustrated as associated with the inter-locking mechanism. The generator has a sludge drain cock 47 provided with an operating handle 48, and also has a water filler funnel 49 provided with an operating valve handle 50. A vertically disposed rock shaft 51 has a locking arm 52 which when in the position shown prevents the operation of either of the valve handles 48 or 50. This rock shaft 51 at its upper end 115 120 125 130 135

has a member 53 which is so designed and so mounted that the rock shaft cannot be oscillated except when the gas valve and carbide feed valves are closed. Thus the opening of the last mentioned valves not only prevents the release of the running gear, but also prevents the opening of the drain and water filler valves.

The non-rotatable supports 18 when in operation, that is when the wheel 17 is lifted, constitute means for preventing transporting movement of the generator. The catch 43 serves to lock these parts in position with the wheel 16 raised. The bar 39 when withdrawn serves as a means for locking the valves against opening movements when the wheel 17 of the generator is in lower or operative position. The bar 37 serves as another means for preventing lowering movement of the wheel 17 when the valves are open.

So far as concerns certain broad features of my invention, it will be evident that other locking means than the catch 43 and the raising of the wheel 17 might be employed for preventing movement of the truck, and which instead of lifting a wheel off the floor might operate to prevent rotation of the wheel or otherwise prevent or interfere with the free movement of the truck.

In my copending application Serial No. 39,177, filed June 24, 1925, I have described a construction in which a pivoted lever may either support a lower carbide feed valve, such as the valve 23, or may act on the stem of an upper valve such as the valve 22, to positively close the latter. By the term carbide feed valve as used in the present case, I include either a valve such as 22 when operated as described in the other application, or such a valve as the valve 23 shown in this application, or any other equivalent mechanism for positively preventing the feed of the carbide and thus controlling the operation of the generator.

Having thus described my invention, what I claim as new and desire to secure by Letters Patent is:—

1. A portable acetylene generator having a generator controlling member, means for locking the same, a truck for supporting the generator, and having running gear, means for locking said running gear, and means for preventing the release of the first mentioned locking means when the running gear is unlocked.

2. A portable acetylene generator having a generator controlling member, means for locking the same, a truck for supporting the generator and having running gear, means for locking said running gear, and means for preventing the unlocking of the running gear when said controlling member is unlocked.

3. A portable acetylene generator hav-

ing a generator controlling member, a generator support including a rotatable member and a non-rotatable member adapted to act alternately, and means for preventing actuation of said first mentioned member when said rotatable supporting member is in operation.

4. A portable acetylene generator having a generator controlling member, a generator support including a rotatable member and a non-rotatable member adapted to act alternately, and means for preventing the movement of said rotatable supporting member into operative position when said first mentioned member is in a position permitting normal operation of the generator.

5. A portable acetylene generator having a generator controlling member, a generator support including a rotatable member and a non-rotatable member adapted to act alternately, and means for preventing the shifting of the weight of the generator from said non-rotatable support to said rotatable support, or vice versa, when said generator controlling member is in a position permitting normal operation of the generator.

6. A portable acetylene generator including a generator controlling member, a generator support including a rotatable member and a non-rotatable member adapted to act alternately, a catch for holding said rotatable supporting member in inoperative position, and means for preventing the actuation of said first mentioned member when said catch is in released position.

7. A portable acetylene generator including a generator controlling member, a generator support including a rotatable member and a non-rotatable member adapted to act alternately, a catch for holding said rotatable supporting member in inoperative position, and means for preventing the release of said catch when said first mentioned member is in a position permitting normal operation of the generator.

8. A portable acetylene generator including a supporting truck having running gear, a gas outlet valve, and means for locking the running gear to prevent operation when said gas outlet valve is open.

9. A portable acetylene generator including a supporting truck having running gear, a carbide feed valve, and means for locking the running gear to prevent operation when said carbide feed valve is open.

10. A portable acetylene generator having running gear for supporting the same, a gas outlet valve, means for rendering said running gear operative or inoperative, and means for preventing the opening of said valve when said running gear is in operative position.

11. A portable acetylene generator having running gear for supporting the same, a carbide feed valve, means for rendering said

running gear operative or inoperative, and means for preventing the opening of said valve when said running gear is in operative position.

5 12. A portable acetylene generator having supporting means including running gear, a draft handle, a generator controlling member, a catch for holding the handle in inoperative position for pulling purposes, and means for preventing the release of said catch when said controlling member is in a position permitting normal operation of the generator.

15 13. A portable acetylene generator having supporting means including running gear, a draft handle, a gas outlet valve, a catch for holding the handle in inoperative position for pulling purposes, and means for preventing the release of said catch when

20 the valve is in open position.

14. A portable acetylene generator having supporting means including running gear, a draft handle, a carbide feed valve, a catch for holding the handle in inoperative position for pulling purposes, and means for preventing the release of said catch when the valve is in open position.

25 15. A portable acetylene generator having supporting means including a supporting leg, a supporting wheel, means for varying the relative elevations of said leg and wheel to bring either into and the other out of operation, a generator controlling valve, and means for preventing actuation of the valve when the supporting wheel is in operative position.

30 16. A portable acetylene generator having supporting means including a supporting leg, a supporting wheel, means for varying the relative elevations of said leg and wheel to bring either into and the other out of operation, a generator controlling valve, and means for preventing the movement of said wheel into operative position when said

35 40 45 valve is open.

17. A portable acetylene generator having a supporting truck, a draft handle, a controlling valve, a locking bolt operatively

connected to the valve, a catch for holding the draft handle in raised position, and a movable member operatively connected to said catch and having an aperture adapted to receive said locking bolt.

5 18. A portable acetylene generator having a control valve, a locking bolt operatively connected thereto, a supporting wheel adapted to be moved into or out of operative position, and means for preventing movement of said wheel into operative position when the valve is open, and including a member having an aperture to receive said locking bolt.

60 19. A portable acetylene generator including a truck having a steering wheel, a steering post, a pivoted member in which said post is mounted, a handle for turning said member, an apertured member operatively connected to said first mentioned member, a generator controlling element, and a locking bolt connected to said element and adapted 65 to enter an aperture of said second mentioned member.

70 20. A portable acetylene generator having a carbide feed valve, a gas outlet valve, a locking bolt, connections between said valves 75 and said bolt for operating them simultaneously, a supporting truck having a supporting wheel, a pivoted member for connecting the wheel and the truck, a draft handle for oscillating said member to bring said wheel 80 into or out of operative position, a catch for normally holding said draft handle in raised position, an apertured plate in operative relationship to said locking bolt, means for moving said last mentioned member to bring 85 the aperture thereof out of registry with the bolt upon the actuation of said catch to permit lowering of the draft handle, and means for preventing the return movement of the catch after the lowering of the draft 90 handle and the movement of said supporting wheel into operative position.

Signed at Grand Haven in the county of Ottawa and State of Michigan this 22nd day of July, A. D. 1925.

EARL M. EVLETH.
